CLAIM

The ornamental design for a game decorative tumbler cup, as shown and described.

DESCRIPTION

FIG. 1 is an isometric view of a game decorative tumbler cup showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof;

FIG. 7 is an operational isometric view thereof; and,

FIG. 8 is a rear elevational view thereof showing my design. The broken line showing of a hand in FIG. 7 is included for the purpose of illustrating environment and forms no part of the claimed design.
